UNITED STATES PATENT OFFICE.

CHARLES O. MATHEWS, OF MILFORD, CONNECTICUT.

DESIGN FOR A TAIL-LIGHT FOR AUTOMOBILES.

53,248.

Specification for Design.

Patented Apr. 29, 1919.

Application filed January 18, 1919. Serial No. 271,930. Term of patent 7 years.

To all whom it may concern:

Be it known that I, CHARLES O. MATHEWS, a citizen of the United States, residing at the town of Milford, in the county of New Haven and State of Connecticut, have invented a new, original, and ornamental Design for a Tail-Light for Automobiles, of which the following is a specification, reference being had to the accompanying drawing, forming part thereof, in which

Figure 1 is an elevation of a tail light showing my new design,

Fig. 2 a plan view of the same, and

Fig. 3 an elevation of the structure, as seen from a slightly different angle from that shown in Fig. 1.

I claim—

The ornamental design for a tail light for automobiles, as shown.

CHARLES O. MATHEWS.
